COMBINED NIGHT LIGHT AND DRYING RACK FOR CONDIMENT DISPENSERS

Edward A. Speciale, 270 NE. 105th St.,
Miami Shores, Fla.

Filed Oct. 31, 1961, Ser. No. 67,324

Term of patent 14 years

(Cl. D44—29)

FIG. 1

FIG. 2

FIG. 3

FIG. 4

The essential features of my design are shown in full lines.

I claim:

The ornamental design for a combined night light and drying rack for condiment dispensers, substantially as shown and described.
